ORNAMENTAL STITCH ATTACHMENT FOR
SEWING-MACHINES

Victor J. Sigoda, New York, N. Y.

Application October 22, 1929, Serial No. 401,427

8 Claims. (Cl. 112—98)

This invention relates to sewing machines, and is illustrated, by way of example, as embodied in a Singer sewing machine of a well-known kind whereby lock stitches are produced.

5 An object of the invention is the provision of improved mechanism for doing ornamental stitching in conjunction with the production of lock stitching, or any kind or style of stitching with which an ornamental effect may be obtained.

10 Another object of the invention is the provision of an attachment of improved construction for producing ornamental stitching and securing the stitches thereof by the stitches produced by the machine to which the attachment is applied.

15 A further object of the invention is the provision of a mechanism of the character described for doing ornamental work with threads consisting wholly or partially of cotton, wool, silk, tinsel or other suitable material.

20 The invention has for a still further object the provision of a construction in which the needle is mounted and operated to move in line with the direction of the movement of the material being sewed and furnishes loops in positions where they will be engaged and secured by the sewing needle in the process of the usual sewing operation.

25 My invention also relates to a construction having means whereby the ornamental stitching mechanism may, at will, be put into or out of operation during the operation of the sewing machine.

30 Other objects and advantages of my invention will appear hereinafter.

35 The invention consists in the improved mechanism for doing ornamental work, and in the form, construction and relative arrangement or arrangements of parts, as will be hereinafter described and subsequently incorporated in the subjoined claims.

40 The invention will be best understood by referring to the accompanying drawings which form a material part of this application, and in which—

45 Figure 1 represents a rear elevational view of a sewing machine fitted with my improvements and partly in section;

50 Fig. 2 is an underneath plan view of the parts shown in Fig. 1;

55 Fig. 3 is a detail sectional view, taken on the line 3—3 of Fig. 1;

Fig. 4 is a similar view, taken on the line 4—4 of Fig. 1;

Fig. 5 is a fragmentary elevation, showing the

controlling device whereby the ornamental stitching mechanism is disconnected from the cam drive;

Fig. 6 is a right hand end elevation of the two part presser foot construction;

Fig. 7 is a top view and section of the presser foot construction in connection with the needle for producing the ornamental stitching;

Fig. 8, 9 and 10 are detail perspective views, showing progressive positions of the cooperating needles; and

Fig. 11 and 12 are top and underneath plan views, respectively, of a fragment of goods, showing the ornamental stitching produced by my improved mechanism.

Referring in detail to the accompanying drawings, and first to Figs. 1 and 2, 15 designates the bed plate, 16 the overhanging arm, 17 the sewing needle, 18 the driving wheel, 19 a rotary shaft constituting part of the driven transmission, 20 the feed driving rock shaft, and 21 the hook driving shaft having a sewing hook 21', all of these parts being of the usual construction and operated in the customary way.

My invention, in its preferred form of construction as illustrated in the drawings, comprises a holder 22 for an auxiliary needle 23 adapted to employ an ornamental thread whereby to embellish the material being sewed. The ornamental thread may consist wholly or partly of cotton, wool, silk, or tinsel. The holder 22 is formed with an upwardly and inwardly curved portion 24 in which the needle 23 is removably secured. With the holder 24 is formed an intermediate transversely extending axis part 25 which is mounted by means of trunnions or pivot pins 26 between the depending arms 27 provided on a tubular member 28, herein shown as turnably fitted on the vertical post 29 between the upper and lower collars 30 and 31. Said post 29 comprises a vertical axis for the horizontal oscillation of the tubular member 28, arms 27 and holder 22, and its upper end is secured at 33 in the bed plate 15.

With the transverse axis portion 25 of the holder is formed an arm 34 which curves upwardly and inwardly as best shown in Fig. 1. Connected to the end of the arm 34 by a suitable ball and socket joint 35 is a connecting rod 36, the opposite end of which is connected in turn through a ball and socket joint 37 with one arm 38 of a bell crank lever indicated generically at 39. Said bell crank lever has a hub portion 40 which is mounted for turning and axially sliding movement upon a pin 41 secured in the framing

42 of the machine. The opposite arm 43 of the bell crank lever carries a follower device in the form of a pin 44 carrying a roller 45 engaging in a cam groove 46 cut in the face of the gear wheel 47. A gear wheel 48, which drives the gear wheel 47, receives its power from a pinion 49 fixed upon the driven shaft 19. By this construction and arrangement, when the sewing machine is operated so as to reciprocate the sewing needle 17 in the usual way, power is taken from the driven shaft 19 for the purpose of rocking the holder 22 upon its transverse axis. When the follower engages the cam groove portion 50, the holder is rocked in a direction to pass the needle 23 through the material 51 and toward the sewing needle 17 and at an angle with respect thereto. Now the needle 23 carries the ornamental thread 52 through the material being sewed and in such manner that on the return stroke of the needle 23 a loop 53 (see Figs. 8 and 9) is produced in a position where the sewing needle 17, as it descends, will enter the loop 53 and thereupon secure it flat upon the material 51 and under the line of stitching 54.

25 To facilitate the entrance of the sewing needle 17 into the loop 53 and to guard positively against the possibility of the loop thread becoming interposed between the point of the needle 17 and the needle 23, the last-named needle is formed with a head portion 55 and a throat 56 adjacent thereto. The sewing needle 17 is preferably tapered at 57' to a point, the tapering being, as clearly shown in Fig. 9, on the side opposite to that which comes in close proximity to the needle 23. By the provision of the throat 56 a space is provided inside the loop 53, and into this space the tapering end 57' of the needle 17 enters, so that the loop 53 is engaged by the tapering side of the needle 17 underneath the needle thread 57. In this way, as the cooperating needles descend, the loop 53 is engaged by or transferred to the sewing needle so that during the regular sewing operation and in connection with the lateral stitching movement of the needle 17 to produce the zigzag line of stitching 54, the loop 53 will be secured flat upon the face of the material 51, underneath the line of stitching 54 and about the point 58 where the bobbin thread joins the line of stitching. It will of course be realized by those skilled in the art and familiar with the Singer lock stitch sewing machine that the stitch forming mechanism also includes in cooperation with the upper needle 17 an under stitch forming mechanism or sewing hook 21' by means of 55 which to lock stitch in the conventional way the bobbin thread with the stitching 54.

60 As the holder 22 is rocked upon its horizontal axis, it is also given a continuous lateral oscillating movement about the axis of the vertical post 29. The purpose of this additional movement is to cause the needle to move in the same direction as the movement of the material 51 so that the needle 23 will not retard or hold back the material 51 as it is being sewed in the customary way. The power for effecting the oscillating movement of the holder and needle is taken from the feed driving rock shaft 20. The connecting transmission means to this end comprises a collar 59 secured to said rock shaft 20 and a connecting arm 60 which is connected at one end by a ball and socket joint 61 with the collar 59, and at the other end by a ball and socket joint 62 with the end of a connecting rod 63. The opposite end of the connecting rod 63 is secured by 75 a band 64 to the tubular portion 28, this ar-

angement being such that the arms 27 and consequently the holder 22 will be oscillated laterally from the rocking movements of the feed driving rock shaft 20. Under this arrangement, under which the needle is caused to move in line with the movement of the material, the withdrawing action of the needle 23 takes place through the material being sewed at substantially the same place where it entered such material, as shown at 65 in Figs. 11 and 12. In this way, 10 as the needle 23 penetrates the material being sewed so as to carry its loop to the sewing needle 17, the said needle 23 advances in line with the material and returns substantially at the place of penetration, leaving behind upon the sewing 15 needle the loop 53 which is secured flat upon the material. Manifestly, the number of loops that may be produced upon the material during the sewing thereof depends upon the ratio of the gear wheels included in the transmission and operated from the driven shaft 19.

According to a feature of my present invention, provision is made whereby, at will, the follower may be withdrawn from the cam groove during the customary operation of the machine. In the present embodiment, this result is obtained by means of a pull shaft 66 mounted for longitudinal sliding movement in a bearing device 67 and carrying at the outer side of the framing 42 a cross pin 68. A head piece 69 associated with the bearing device 67 at the outer end thereof is provided at its outer end with a pair of intersecting slots 70 and 71 adapted to receive the cross pin 68. At its inner end the pull shaft 66 turns in a head 72 provided with an arm 73 slidably fitting upon the pin 41 between the bell crank hub 43 and a collar 74. Imprisoned between the collar 74 and the framing 42 is a coiled spring 75 which normally urges the bell crank lever into that position where the follower will engage in the cam groove and where the cross pin 68 will occupy a position in the bottom of the slot 70. Now the other slot 71 is of less depth than the slot 70, so that when the pull shaft 66 is drawn outwardly and the cross pin 45 engaged in the shallow slot 71, the follower will be maintained out of engagement with the cam groove. This operation does not interfere in any way with the operation of the sewing machine or with the continuous lateral oscillation of the 50 holder.

In carrying out my invention, it is of course necessary to make provision for sewing materials which differ in thickness. It is also necessary to carry out such provision in a manner that will avoid any likelihood of bending the needle 23, which, as has been previously observed, is given two movements, one upwardly through the material being sewed toward the sewing needle and at an angle thereto, and the other a lateral movement in line with the movement of the material. To this end I may provide two cooperating presser foot plates 76 and 77, the plate 77 being arranged to make pressure upon material considerably thicker than the material 51. The shanks 78 and 79 of the presser foot plates 76 and 77, are adjustable respectively, in the holders 80 and 81, associated with the bar 32 carrying the usual bar spring 33. Adjustment of the shank 78 is effected by manipulating the set screws 83', while the holder 81 is provided with a set screw 84 for securing the shank 79 in the adjusted position desired. A strike pin 85, secured in the holder 80 at the adjusted position desired and by means of set screws 86, is 75

adapted, as the spring 83 is subjected to compression due to pressural contact of the plate 76 with the work, to engage the set screw 84 whereby the plate 77 will be resiliently forced upon the work with the result that the two plates 76 and 77 will exert substantially even pressure upon the materials to be stitched. The presser foot plate 76 is provided with a slot or opening 87 for the movement of the needle 23 therethrough. On its upward stroke, the needle 23 passes through the forward end portion of the slot 87 as shown in Fig. 8, whereas on its withdrawing movement the said needle 23 passes through the rear end portion of said slot as illustrated in Fig. 9. Owing to the provision of two presser foot devices, separately adjustable, the presser foot plate 76 may be so adjusted that the slot or opening 87 will provide for the movements of the needle 23 without any danger of bending the latter; irrespective of any differences in the thickness of materials placed under the presser foot plates 76 and 77. Associated with the presser foot plate 77 is a guide 88 having a down turned portion 89 for guiding the edge 90 of the material 51. Where another piece of material (not shown) which is to be sewed to the material 51, is to pass underneath the presser foot plate 77, the guide 88 is reversed so that the portion 89 thereof projects upwardly while the opposite end portion 91 works on top of the material instead of along the edge.

Suitable provision may be made to prevent axial movement of the bell crank hub 40 for engaging the follower with, or disengaging it from, the cam groove when the needle holder 22 is at a position other than its low terminal of movement or approximately so, that is to say, when the needle 23 is at a position other than a retracted position below the material being sewed. In the present exemplification the means to this end is shown in Fig. 2 as comprising a strike piece 91' attached at one end by screws 92 to the bed plate and provided at its opposite free end with an open notch 93. The bell crank arm 38 cooperates with this open notch and the character of the cooperation is such that it can operate freely in the open notch when the follower is engaged in the cam groove and can clear the end of the strike piece 91' only when the needle 23 is at its lower terminal of movement. When it is attempted to move the bell crank hub axially, either to apply or withdraw the follower, with the needle 23 at any position other than its low terminal of movement, such attempt will be frustrated since the arm 38 will slidingly engage the end of the strike piece. By this arrangement the vertical rocking movement of the needle 23 about its horizontal axis cannot be started or ended while the needle is engaged with the material being sewed. The sewing machine can, therefore, be operated either with or without my ornamental stitch attachment.

From the foregoing description, taken in connection with the accompanying drawings, it will be manifest that I have disclosed an extremely simple attachment for producing ornamental stitches in connection with the sewing of materials in the regular way, and one which embodies the several features of advantage enumerated in the statement of invention. While I have, in the present instance, shown and described a preferred embodiment of my invention as reduced to practice, it is to be understood that the construction is susceptible of modification in various particulars without departing from the

spirit or scope of my invention or sacrificing any of its advantages. I claim:

1. The combination in a sewing machine, consisting of a part mounted for oscillation on its axis and provided with a pair of arms, a needle holder pivoted between the arms for rocking movement, means for oscillating said part, operative means in connection with said first means, means for rocking said holder adapted to be operated by a moving part of the sewing machine, said holder having an upwardly and inwardly curved end, and a needle held in said end, to be moved in line with the direction of the movement of the material being sewed, consequent upon the oscillation of said holder, and to be passed through the material being sewed, consequent upon the rocking of the holder.

2. The combination in a sewing machine of the character described, embodying stitch forming means including a sewing needle and feeding mechanism for the material to be sewed, of an auxiliary loop carrying needle constructed and arranged to pass through the material being sewed and to present the loop in a position where it will be entered by the sewing needle and secured with the stitching produced thereby, means for moving the auxiliary needle through the material, operative transmission means in connection with said first means, and means operated by the feeding mechanism for oscillating the auxiliary needle in line with the direction of feed of the material being sewed.

3. In a sewing machine, the combination with an auxiliary needle holder pivotally mounted to have rocking movement, of a gear wheel adapted to be rotated by a driving part of the sewing machine and provided with a cam groove, a bell crank mounted to have rocking movement on its axis and slidably adjustable with said gear wheel, a follower on one arm of said bell crank engaging said cam groove, and an operative connection between the opposite arm of the bell crank and said holder whereby to effect rocking action of said holder from the rotation of said wheel.

4. In a sewing machine, the combination of a wheel adapted to be rotated by a driving part of the sewing machine and provided with a cam groove, a bell crank mounted to have rocking and sliding movement on its axis, a follower on one arm of said bell crank engaging said cam groove, a needle holder mounted to have rocking movement, an operative connection between the opposite arm of the bell crank and said holder whereby to effect rocking action of said holder from the rotation of said wheel, and means for sliding the bell crank on its axis so as to disengage the follower from said cam groove.

5. A sewing machine having, in combination, stitch forming mechanism including an upper needle reciprocating through the work below it and under stitch forming mechanism to cooperate with it and forming a course of stitching upon the work, an under embroidery needle device reciprocating through the work above it and forming above the same embroidery loops each of which is penetrated by the upper needle and secured in place upon the work by the stitching formed thereon by said upper needle, said device being effective to penetrate the work at points spaced laterally a distance from the course of stitching and to move above the work from such points to deliver to the upper needle the loops which are to be secured by the stitching when the stitching is secured by the under stitch forming

mechanism, whereby to position upon the work embroidery loops lateral to the course of stitching and between the securing stitching and points of penetration made through the work by 5 said device.

6. A sewing machine having, in combination, stitch forming mechanism including an upper needle reciprocating through the work below it and under stitch forming mechanism to cooperate with it and establishing stitching upon the work, an under embroidery needle device reciprocating through the work above it and cooperating with the upper needle at an angle to form embroidery loops upon the top of the work, 10 extending from the stitching to a point laterally thereof, the upper needle being effective with respect to the lower needle to penetrate through each embroidery loop to secure the same at one end by the stitching while the lower needle secures the opposite portion of the loop at its laterally distant point by carrying it through the work to the lower side thereof.

7. A sewing machine having, in combination, stitch forming mechanism including an upper needle which reciprocates through the work below it and under stitch forming mechanism to cooperate with it to produce upon the work a succession of stitches, an under embroidery needle device reciprocating through the work above it

and cooperating with the upper needle at an angle to form upon the top of the work a flat lateral embroidery loop penetrated at least by one of the stitches, and means for operating said device in timed cooperation with the upper needle to produce only one embroidery loop to a plurality of stitches. 5

8. In a sewing machine, the combination of stitch forming mechanism including an upper needle, under stitch forming mechanism, means 10 for operating the first-named stitch forming mechanism to reciprocate the needle through the work below it, means for operating the under stitch forming mechanism to cooperate with the upper needle in making the stitches, means for 15 forming embroidery loops to be secured by the stitches being formed and to extend upon the work laterally therefrom, comprising an under reciprocating needle operative to penetrate the work a spaced distance laterally of the stitches 20 and having movement to the upper needle to form embroidery loops thereon, and means for operating said under needle in timed ratio to the upper needle and under stitch forming mechanism to produce spaced lateral loops connected 25 at one end to the formed stitches and passing through the work at the other end.

VICTOR J. SIGODA.
